(57) CLAIM

The ornamental design for a facial massage tool, as shown and described.

DESCRIPTION

FIG. 1 is a front perspective view showing the new, original, and ornamental design of a facial massage tool;

FIG. 2. is a front side elevation view thereof;

FIG. 3. is a rear side elevation view thereof;

FIG. 4. is a left side elevation view thereof;

FIG. 5. is a right side elevation view thereof;

FIG. 6. is a top plan view thereof; and,

FIG. 7 is a bottom plan view thereof.

The broken lines shown in the drawings represent environmental subject matter and form no part of the claimed design.
